[57] **CLAIM**

The ornamental design for a cutting torch guide and alignment device, as shown and described.

DESCRIPTION

FIG. 1 is a front perspective view of a cutting torch guide and alignment device showing our new design, with a cutting torch shown in broken lines for illustrative purposes only;

FIG. 2 is a right side perspective view;

FIG. 3 is a bottom perspective view;

FIG. 4 is a left side perspective view; and

FIG. 5 is a front and left side perspective view thereof.

The rear is conventional in appearance.

FIG. 1

FIG. 3

FIG. 2

FIG. 4
